FASTENING-INSERTING MACHINE

John T. Lancaster, Newton, Mass., assignor to
United Shoe Machinery Corporation, Borough
of Flemington, N. J., a corporation of New Jersey

Application November 7, 1939, Serial No. 303,246

20 Claims.

(Cl. 1—32)

My invention relates to machines by which nails or other fastenings may be inserted for securing work-pieces. An example of work for which the machine is well adapted is the attachment of heels to shoes. The invention is concerned especially with the delivering of the fastenings to the support for the work in preparation for the inserting operation.

In Letters Patent of the United States No. 1,785,928, Benjamin, December 23, 1930, is disclosed a heel-attaching machine, in which nails are delivered to the passages in a work-supporting jack by a slide carrying a nail-holding block and arranged to reciprocate in the machine-frame between a nail-receiving position and a position in which the nails are delivered to the jack. The slide is driven through slipping clutch mechanism, which urges it against stops at its opposite extremes of travel. The discharge of the 20 nails into the support from the block is controlled by a retaining shutter, normally closed by a spring and operated during the travel of the loader-block by its contact with a relatively fixed point. It is an object of my invention to increase, by the use of simple mechanism, the smoothness and positiveness of action of an organization of this character.

As a feature by which this end is gained, my improved loading or fastening-transferring mechanism combines with a reciprocatory carrier for fastenings, a rotatable shaft, a cam normally loose upon the shaft and connected to the carrier to control its reciprocation constantly, clutch mechanism for causing the connection of the cam to the shaft, and a member movable by the operator to govern the clutch mechanism. By this means, upon engagement of the clutch by the operator, the cam mechanism advances and retracts the transferring mechanism with exactly the desired timing, wholly without shock tending to displace the fastenings, and minimizing wear which would cause variable action. In the particular form of the invention herein disclosed, the clutch mechanism includes a latch movable upon the cam to either free or engage a driving connection to the shaft, this clutch being governed by its engagement with a cam upon a lever movable by the operator.

As another feature of the invention a member, by which fastenings for use in an inserting machine may be retained temporarily or released as to their relation to passages in a fastening-carrier, is moved under the power of the machine when the carrier is at rest with its passages registering with those in the work-support of the ma-

chine. Because of this complete freedom from movement at the time of fastening-delivery, the two sets of passages may be in exact alinement during the entire delivery-period, and there is no opportunity for the fastenings to be incorrectly presented to the passages in the support. The power-movement of the retaining member is preferably effected by a rotatable cam. I have illustrated herein a slide guided to reciprocate in the frame of the machine and carrying a loader-block having nail-receiving passages, a slide guided upon the loader-slide and provided with a shutter controlling the loader-block-passages, and a rotatable cam acting upon the shutter-slide through a lever fulcrumed upon the frame. There are thus furnished, in connection with the feature previously mentioned, cams for actuating both the carrier or loader and the retaining member or shutter, which cams may be in the form of grooves in a disk. This disk may be normally loose upon a rotatable shaft and controlled by the operator through clutch mechanism, as already indicated.

In the accompanying drawings,

Fig. 1 shows a top plan view of one form of my invention as it would be applied to a heel-attaching machine;

Fig. 2, a front elevation thereof, including the jack of the machine;

Fig. 3, a side elevation of the parts of Fig. 2, with the addition of a work-holddown co-operating with the jack;

Fig. 4, a sectional detail of the clutch mechanism on the line IV—IV of Fig. 1; and

Fig. 5, a detail in perspective of the latch-controlling cam upon the starting lever.

There appears in the drawings, elements of the nail-transferring or loading mechanism of a heel-attaching machine, which machine may resemble, generally, that of the previously mentioned patent. These elements include a frame-column 10, at the front of which is mounted a work-supporting jack 12, having a set of vertical passages 14 containing reciprocatory drivers 16. To these passages is to be delivered a load of nails N, the heads of which will rest upon the upper ends of the drivers in preparation for being inserted through the heel-seat of a jacked shoe S to secure thereto a heel H. During this operation, abutments 18, carried by a vertically movable clamping head, hold the work against upward displacement under the influence of the nail-driving force. Before the jacking of the shoe, delivery of the nails to the passages 14 is made by a loader-block 20 secured at the forward extremity of a

slide 22, guided in the column 10 for horizontal reciprocation. The nails are carried in vertical passages 24 in the block and retained by a shutter 26 movable against the lower surface of said block. The shutter is normally held across the block-passages, but may be moved from beneath the block for the delivery of the contained nails. To the block-passages nails are supplied, when the block is in its rearward position, from an un-10 illustrated distributor, through tubes 28 and a foot-plate 30, the discharge being controlled by the customary perforated shutter 32 slidable beneath the foot-plate. This shutter 32 may be moved to bring the openings through it into 15 alignment with the foot-plate-passages, so nails may fall into the loader-block-passages, by such a controlling mechanism as that of Letters Patent of the United States No. 1,947,770, MacKenzie, February 20, 1934. To transfer the load of nails 20 in the block 20 to the passages 14 of the jack, the slide 22 is reciprocated under the control of an operator-actuated lever 34, through gearing G, later to be described in detail, from a shaft 36 journaled horizontally across the frame-column. The shaft is driven continually from the 25 main power-shaft of the machine by way of a vertical shaft 38, worm-gearing 40, a horizontal shaft 42 and worm-gearing 44.

Now considering the elements more closely relating to this invention, the gearing G includes 30 a rack 50 formed at the under side of the loader-slide 22 and having meshing with it a gear 52, fast upon one extremity of a sleeve 54 rotatable about the shaft 36. At the opposite end of the 35 sleeve a pinion 56 is secured, this meshing with gear-segment 58 free to turn about a spindle 60, which is mounted to oscillate upon the column 10. Rotatable upon the outer side of the segment is a roll 62 lying in a cam-groove 64, formed in a 40 disk 66 surrounding the shaft 36. The contour of the groove is preferably such, that from its resting position beneath the foot-plate 30, the block 20 with its load of nails will be advanced rapidly until it approaches the top of the jack 45 12. Then its movement is slowed, and it is brought to rest with its passages 24 in registration with the jack-passages 14 and is held until the contained load of nails has been discharged into said jack-passages. This having been accomplished, the cam-groove reverses the travel 50 of the loader-block, so it is rapidly returned to its initial position.

The shutter 26 of the loader-block is reciprocated in the proper time-relation to the block 55 movement, by means which will now be described. This shutter has a rearward extension 70 arranged to slide in a longitudinal groove in the loader-slide 22. When the loader-block is beneath the foot-plate 30 with its passages 24 regis-60 tering with the nail-supplying passages in the foot-plate, the shutter 32 of which has been opened as previously indicated, the shutter 26 of the loader-block is closed by its engagement with a stop-screw 72 threaded horizontally 65 through the frame. This position of the shutter is more definitely determined by a plunger 74, movable vertically in the loader-slide 22 and forced up by a leaf-spring 76 engaging its lower end. With the shutter in its initial nail-retain-70 ing relation, the rounded upper end of the plunger enters a depression 78 in the shutter-slide 70. This latching means will yield, when the slide 70 is moved positively, to release the nails. A load of nails is thus received and temporarily retained 75 in the block-passages at the opposite extreme of

travel of the loader-block, when it has come to rest under the control of the cam-groove 64 with its passages vertically aligned with the jack-passages 14. The shutter 26 is moved in the following manner to cause the opening of the block-passages. The spindle 60 has secured to its inner extremity an arm 80, which at its free end is pivoted to one arm of a bell-crank-lever 82 turning upon a fixed fulcrum 84. The other arm of the bell-crank extends downwardly to a point 10 just above the shutter-slide 70, where it has a lateral projection 86 lying above said slide and in horizontal alinement with an upward projection 88 therefrom. Fast upon the outer end of the spindle 60 is an arm 90 extending over the periphery of the disk 66 and then downwardly, carrying at its inner side a roll 92 lying in a cam-groove 94 in the disk. This groove is so formed that, while the loader-block is traveling under the influence of the cam-groove 64, the projection 86 will remain inactive. When, however, the loader-block has arrived over the jack 12 and is held stationary by the cam-groove 64, the groove 94, through the arms 90 and 80, acts upon the lever 82 to urge its projection 86 against the 15 shutter-slide-projection 88, which has reached a point adjacent to said projection 86. The shutter-slide is thereby moved to the left, as viewed in Fig. 3 of the drawings, and thus held. 20

The movement is sufficient to carry it from 30 beneath all the block-passages, whatever may be the nailing design. The load of nails, therefore, is released to fall into the jack-passages 14.

To initiate an operating cycle of the loading mechanism, the operator depresses a hand-pad 98 of the lever 34. This lever moves about its fulcrum 100 from a raised position, normally maintained by a tension-spring 102 to an extent permitted by contact with the shaft 36 of the upper end of a slot 104 in the wall of a casing 106 formed upon the lever. The descent of the lever causes clutch mechanism C (Fig. 4) to join the constantly rotating shaft 36 to the cam-disk 66. When the lever 34 is raised by the spring 102 to a point determined by engagement of the lower extremity of the slot 104 with the shaft, a cam-face 110 (Fig. 5) upon a disk 112, attached to the inner face of the lever-casing, so holds a latching member 114, that, through a space 116 in it, a projection 118 secured to the shaft 36 50 may revolve freely. The latch is guided to slide horizontally in the hub of the cam-disk. At the outer end of the latch is a surface 120, which, by its contact with the cam-surface 110, determines the position of the space 116, this contact 55 being maintained by an expansion-spring 122 seated in a bore in the disk-hub and bearing against the latch. The normal relation of the disk 66, and its respective loader-actuating and shutter-actuating grooves 64 and 94, is fixed 60 by engagement of the side wall of the latch adjacent to the surface 120 with a radial wall 124, which projects from the highest or resting point of the cam-surface 110. The wall 124 is of such limited radial extent, that upon depression of the hand-lever said wall leaves the latch 114, so the latter is urged by its spring 122 against the low portion of the cam-surface 110. This carries the latch-space 116 away from the shaft-projection 118, and, as said projection is revolved by the shaft, it strikes the side wall of the latch and turns the cam-disk through 360°. This movement is stopped when the high point of the cam-surface 110 again has so located the latch 70 75

that the shaft-projection travels through the latch-space.

To outline briefly the operation of my improved loading mechanism for fastening-inserting machines, there having been accomplished the attachment of a heel H to a shoe S by a load of nails N, previously delivered to the jack-passages 14, the operator removes the work from the jack and depresses the pad 98 of the lever 34 in a direction parallel to the plane of rotation of the cam-disk 66. By the action of the lever-cam member 112 upon the latch 114 of the clutch mechanism C, the cam-disk is caused to be driven through a complete turn by the constantly rotating shaft 36. In the resting position of the disk, its cam-groove 64, by its action upon the gearing G, is holding the loader-block with its passages 24 alined with the passages in the foot-plate 30. The shutter 32 of the foot-plate has been opened and a load of nails, which it supported, delivered to the loader-block-passages. The picker mechanism of the distributor of the heel-attaching machine may be prepared for supplying each load of nails to the foot-plate through the tubes 28, by the downward movement of a rod 130, the lower extremity of which is joined to a lever 132. This lever is shown as fulcrumed about the spindle 60 and carries a roll 134 contacting with the periphery of a cam 136 fast upon the sleeve 54. The loader-block-shutter 26 is at this time closed because of its engagement with the stop-screw 72. As the cam-disk 66 rotates, the effect of the groove 64 is to start the forward travel of the loader-block, accelerate it to a relatively high speed, then reduce it as it approaches the jack 12, and bring it to a full stop with its passages in registration with the jack-passages 14. During this advance of the loader-block, the projection 86 upon the lever 82, controlled by the cam-groove 94, is held stationary, but, when the loader-block is at rest above the jack and the shutter-slide-projection 88 is in proximity to the lever-projection 80, the groove 94 moves said lever-projection against the slide-projection, thereby opening the shutter to allow the nails N to drop into the jack-passages. Finally, the cam-groove 64 effects the rapid return of the loader-block to its initial position, and the shutter is closed as it contacts with the stop-screw 72 and is retained against accidental displacement by engagement with its slide-depression 78 of the plunger 74. After actuation of the hand-lever 34 it was at once freed by the operator, and when the cam-disk has made its full turn the lever-cam-surface 110 so shifts the latch 114 that the cam-disk 66 is disconnected from the driving shaft and stopped in a predetermined position, with the loading mechanism in its normal relation ready for the succeeding cycle.

Having described my invention, what I claim as new and desire to secure by Letters Patent of the United States is:

65 1. Fastening-transferring mechanism comprising a reciprocatory fastening-carrier, a rotatable shaft, a cam normally loose upon the shaft and connected to the carrier to control its reciprocation constantly, clutch mechanism for causing the rotation of the cam with the shaft, and a member movable by the operator to govern the clutch mechanism.

70 2. Fastening-transferring mechanism comprising a reciprocatory fastening-carrier, a rotatable shaft, a cam normally loose upon the

shaft and connected to the carrier to control its reciprocation constantly, clutch mechanism for causing the rotation of the cam with the shaft, and a lever movable by the operator and provided with a cam for governing the clutch 5 mechanism.

3. Fastening-transferring mechanism comprising a reciprocatory fastening-carrier, a rotatable shaft having a projection, a cam normally loose upon the shaft and connected to the carrier to control its reciprocation constantly, a latch movable upon a cam to free or engage the shaft-projection, and a member movable by the operator to actuate the latch.

4. Fastening-transferring mechanism comprising a reciprocatory fastening-carrier, a rotatable shaft having a projection, a cam normally loose upon the shaft and connected to the carrier to control its reciprocation, a latch movable upon a cam to free or engage the shaft-projection, and a lever movable by the operator and provided with a cam engaging the latch.

5. Nail-loading mechanism comprising a reciprocatory loader-block, a rotatable shaft having a projection, a cam normally loose upon the shaft and connected to the carrier to control its reciprocation, a latch slidable upon the cam along the shaft and having a space through which the shaft-projection may pass, and a lever movable in a direction parallel to the plane of 30 rotation of the first cam and provided with a cam engaging the latch.

6. In a fastening-inserting machine, fastening-transferring mechanism comprising a movable carrier having fastening-holding passages, 35 a member movable upon the carrier to retain fastenings in the passages or release them therefrom, and means movable under the power of the machine to actuate the retaining member.

7. Fastening-transferring mechanism comprising a movable carrier having fastening-holding passages, a member movable upon the carrier to retain the fastenings in the passages or to release them therefrom, and a cam movable to actuate the retaining member.

8. In a fastening-inserting machine, fastening-transferring mechanism comprising a movable carrier having fastening-holding passages, a member movable upon the carrier to retain fastenings in the passages or release them therefrom, and a cam rotatable under the power of the machine to actuate the retaining member.

9. Fastening-transferring mechanism comprising a movable carrier having fastening-holding passages, a member movable upon the carrier to retain the fastenings in the passages or to release them therefrom, an actuating member into co-operation with which the retaining member moves, and means for moving the actuating member to cause the release of the fastenings 60 from the passages.

10. Nail-loading mechanism comprising a movable loader-block having nail-holding passages, a nail-retaining shutter movable upon the loader-block across the ends of the passages and provided with an extension, a member into co-operation with which the extension is moved by the loader-block, and means for moving the member to engage the extension.

11. In a fastening-inserting machine, a work-support having fastening-receiving passages, a carrier having fastening-passages and movable from a fastening-receiving position to a delivering position with its passages registering with the passages in the work-support, a nail-retaining 75

- member movable across the carrier-passages, and means movable to actuate the retaining member and release the fastenings only when the carrier is at rest with its passages in registration with those of the work-support.
12. In a fastening-inserting machine, a work-support having fastening-receiving passages, a carrier having fastening-passages and movable from a fastening-receiving position to a delivering position with its passages registering with the passages in the work-support, a nail-retaining member movable across the carrier-passages, and means movable under the power of the machine to actuate the retaining member and release the fastenings only when the carrier is at rest with its passages in registration with those of the work-support.
13. In a nailing machine, a work-support having nail-receiving passages, a loader-slide movable from a nail-receiving position to a delivering position over the work-support, a shutter-slide movable upon the loader-slide across the ends of the passages, and a cam movable to actuate the shutter-slide.
14. In a nailing machine, a work-support having nail-receiving passages, a loader-slide movable from a nail-receiving position to a delivering position over the work-support, a shutter-slide movable upon the loader-slide across the ends of the passages, a lever into co-operation with which the shutter-slide moves, and means for oscillating the lever to actuate the slide.
15. In a nailing machine, a work-support having nail-receiving passages, a loader-slide movable from a nail-receiving position to a delivering position over the work-support, a shutter-slide movable upon the loader-slide across the ends of the passages, a lever into co-operation with which the shutter-slide moves, and a rotatable cam by which the lever is oscillated for engagement with the shutter-slide.
16. In a nailing machine, a frame, a work-support mounted upon the frame and having nail-
- receiving passages, a slide guided for reciprocation in the frame, a loader-block mounted upon the slide and having nail-receiving passages movable thereby into registration with the support-passages, a slide guided in the loader-slide and provided with a shutter controlling the loader-slide-passages, and a cam rotatable upon the frame for actuating the shutter-slide.
17. In a nailing machine, a frame, a work-support mounted upon the frame and having nail-receiving passages, a slide guided for reciprocation in the frame, a loader-block mounted upon the slide and having nail-receiving passages movable thereby into registration with the support-passages, a slide guided in the loader-slide and provided with a shutter controlling the loader-slide-passages, a lever fulcrumed upon the frame for engagement with the shutter-slide, and a cam rotatable upon the frame and by which the lever is oscillated.
18. In a fastening-inserting machine, a reciprocating fastening-carrier, a fastening-retaining member movable upon the carrier, a cam movable to actuate the carrier, and a cam movable to actuate the retaining member.
19. In a fastening-inserting machine, a reciprocating fastening-carrier, a fastening-retaining member movable upon the carrier, and a rotatable disk provided with two cam-grooves said grooves being arranged respectively to actuate the carrier and the retaining member.
20. Fastening-transferring mechanism comprising a reciprocating fastening-carrier, a reciprocating fastening-retaining member co-operating with the carrier, a rotatable shaft, a cam-disk normally loose upon the shaft and connected to the carrier to control its reciprocation constantly and the retaining member intermittently, clutch mechanism for causing the rotation of the cam-disk with the shaft, and a member movable by the operator to govern the clutch mechanism.

JOHN T. LANCASTER.
